UNITED STATES PATENT OFFICE.

ANTHONY W. VOLTZ, OF BUFFALO, NEW YORK.

FILE-CASE.

SPECIFICATION forming part of Letters Patent No. 289,042, dated November 27, 1883.

Application filed March 23, 1883. (No model.)

To all whom it may concern:

Be it known that I, ANTHONY W. VOLTZ, of Buffalo, in the county of Erie and State of New York, have invented certain new and useful Improvements on a File-Case; and I do hereby declare that the following description of my said invention, taken in connection with the accompanying sheet of drawings, forms a full, clear, and exact specification, which will enable others skilled in the art to which it app pertains to make and use the same.

My present invention has general reference to improvements on cabinets for valuable papers, documents, &c.; and it consists, essentially, in the novel and peculiar combination of parts and details of construction, as hereinafter first fully set forth and described, and then pointed out in the claims.

In the drawings already mentioned, which serve to illustrate my said invention more fully, Figure 1 is an elevation in perspective of my improved cabinet. Fig. 2 is a transverse sectional elevation in line $y-y$ of Fig. 3. Fig. 3 is a longitudinal sectional elevation in line $x-x$ of Fig. 2. Fig. 4 is a similar view, illustrating the lid in an open position. Fig. 5 is a plan of a fragment of said lid. Fig. 6 is a plan of the locking device on the lid.

Like parts are designated by corresponding letters of reference in all the figures.

This invention has reference to improvements on a document and paper file for which Letters Patent of the United States were recently granted to me; and its object is to overcome several objections and drawbacks in the construction of said document and paper file.

A in the drawings represents a case of suitable construction and dimensions. In the present instance I have illustrated this case in the form of a book, such shape being preferable to any other for many obvious reasons, although the external contour of said case is of little, if any, consequence. This case has the side A', a back, B', and a cover, door, or similar hinged part, B, a lock, L, with key K, being attached to said door in order to enable the secure closing of the cabinet. To the back B' is hinged a lid, C, and within the case are a suitable number of longitudinal partitions, D, forming, in conjunction with division-slats E, a number

of compartments for the reception of the documents, papers, &c., to be filed within said case.

Within the compartments is provided a device, F, for regulating the depth of said compartments, consisting of two slats, F' F'', and two side pieces, as clearly shown in Figs. 1 and 3, said slat F' being provided with a slot-hole, f, for the passage of the hooked portion g of an extractor, G, as shown in said Fig. 1. This regulating device F is arranged to fit closely into the compartments mentioned, so that when placed into the same at any depth it will retain its position.

On the lid C, I provide a locking device, H, consisting of a suitably-constructed sliding catch, having the bolt h, spindle h', and a nose or projection, a, said spindle being constructed to turn and slide in a loop, c, secured to said lid C.

Back of the locking device H is a button, b, to lock the said locking device H in the following manner: When the lid C is in a vertical or open position, the device H lies close to the said lid C. When said lid is turned down, the said device will retain its vertical position, owing to its pendulum-like contour; but it will assume, with reference to the lid C, a position at right angles to said lid, so that the bolt h can be slid into the aperture or recess d in the case, and thus lock the said lid, as shown in Figs. 2 and 3. To prevent the locking device from being moved backward, the button b is turned back of the nose a, this part of the locking of the cabinet being performed when the door B is open.

It will be readily observed that, owing to the depth of the cabinet, the documents in the rear row of compartments cannot be inserted therein or removed therefrom unless there is a sufficient space above the said compartments for that purpose. This would necessitate the construction of a cabinet much higher than necessary to properly hold the papers. It will therefore be readily seen that, on account of the introduction of the hinged lid C, I am enabled to reduce the height of the cabinet to that only necessary for the proper placing of the documents, their insertion and removal being facilitated by opening the lid C.

It will be further observed that, on account

of the introduction of the pendulum-like locking device H, which will automatically operate to move close to the lid C whenever the same is opened, there is practically no obstruction to the placing of the papers, &c., into said rear compartments. This is quite an essential feature in cabinets of the kind described; as well as the introduction of the adjustable bottom to the said compartments, consisting of 10 the frame or frames F, as described.

Having thus fully described my invention, I claim as new and desire to secure to me by Letters Patent of the United States—

1. As a new and improved article of manufacture, the document and paper cabinet, consisting, essentially, of the case A, having the compartments for the reception of said documents, the cover or door B, and the hinged lid C, said lid being provided with a pendent lock- 15

ing device, H, and one or more of the compartments with the adjustable bottom, substantially as described, for the object stated. 20

2. In paper-cabinets, an adjustable bottom for the compartments, consisting of a frame, F, composed of the slotted top rail, F', rail F'', 25 and suitable side pieces, as described, said frame being constructed to fit tightly into said compartment, and arranged to operate in conjunction with a detachable extractor, as and for the purpose stated. 30

In testimony that I claim the foregoing as my invention I have hereto set my hand in the presence of two subscribing witnesses.

ANTHONY W. VOLTZ.
